UNITED STATES PATENT OFFICE.

MARTIN J. WUJEK, OF BUFFALO, NEW YORK, ASSIGNOR TO HARD MFG. CO., OF BUFFALO, NEW YORK.

SHOE FOR THE LEGS OF METAL COTS AND OTHER ARTICLES.

1,420,602.

Specification of Letters Patent. Patented June 20, 1922.

Application filed January 2, 1917. Serial No. 140,006.

To all whom it may concern:

Be it known that I, MARTIN J. WUJEK, a citizen of the United States, residing at Buffalo, in the county of Erie and State 5 of New York, have invented a new and useful Improvement in Shoes for the Legs of Metal Cots and Other Articles, of which the following is a specification.

This invention relates to shoes adapted to 10 be applied to the lower ends of the legs of metal cots and other articles having legs made from pieces of angle iron or metal bars of angular cross section. The ends of the flanges of these legs are thin and do not 15 afford a broad supporting surface and are also apt to have sharp or rough edges which will mar the floor if the cot or other article is moved or slid about on the floor.

The object of this invention is to provide 20 a shoe of simple and inexpensive construction which can be applied to legs of this sort without appreciably increasing the cost of the article and which will form a broad, flat, smooth bearing surface for the leg 25 adapted to readily slide on the floor or supporting surface.

In the accompanying drawings:—

Fig. 1 is a perspective view of one corner 30 of a metal cot or other structure, the leg of which is provided with a shoe embodying this invention.

Fig. 2 is a plan view of the metal blank 35 from which the shoe is formed, showing by dotted lines the lines on which the blank is folded to form the shoe.

Fig. 3 is an inside elevation, full size, of the lower end of the leg and shoe.

Fig. 4 is a sectional elevation thereof on line 4—4, Fig. 5.

Fig. 5 is a sectional plan view thereof on line 5—5, Fig. 3.

A represents the leg of a cot or other article, the same consisting of an angle-shaped metal bar, such as the angle irons commonly 45 employed in the construction of articles of this sort. B represents the shoe which is applied to the lower end of the leg. This shoe has a horizontal end plate or bearing portion 10 which extends across the lower 50 end of the leg and on which the lower edges of the flanges of the leg rest; upright side portions 11 and 12 which extend upwardly from the horizontal bottom portion at the outer sides of the two flanges of the 55 leg; and securing flaps or portions 13 and 14 which extend from the upright edges of

the side portions 11 and 12 and are bent around the upright edges of the flanges of the leg A and bear against the inner faces of said flanges. The side portions and securing flaps or extremities embracing the flanges of the leg prevent lateral displacement of the shoe, and the shoe can be securely retained on the leg and prevented from slipping endwise off of the same by 60 pinching the securing flaps and side portions so as to tightly grip the flanges of the leg. Or, if desired, the securing flaps can be prick-punched or any other suitable expedient adopted for retaining the shoe 65 constructed as described on the leg.

The shoe is readily formed by bending a flat strip of metal or sheet metal blank of the shape shown in Fig. 2 on the lines indicated by dotted lines in said Fig. 2. 75 Since the blanks from which the shoes are formed have parallel side edges and end edges of similar angularity, they can be cut from metal sheets or strips practically without waste of material and since the shoes 80 are formed simply by bending these flat strips or blanks into the shape shown and are secured on the legs without additional fastening means, it will be evident that the shoes can be manufactured and applied to 85 the legs at such small expense as not to appreciably add to the cost of manufacture of the cot or other article. Nevertheless, the shoes provide broad, flat, horizontal surfaces under the ends of the legs by which the legs 90 bear on the floor, thus adapting the cot or other article to slide readily on the floor without scratching or marring the same.

I claim as my invention:

1. A shoe for the ends of legs and the like 95 made of flanged bars, consisting of a metal piece having an end plate extending across the end of the flanged bar, side portions extending upwardly from said end plate in close contact with the outer sides of the 100 flanges of the bar, and securing flaps extending from said side portions around the edges of the flanges of the bar in close contact with the inner sides of said flanges and cooperating with said side portions to 105 grip the flanges of the bar to retain the shoe in place.

2. A shoe for the ends of angle bar legs and the like, consisting of a metal piece which fits over the end of the angle bar 110 and has a triangular end plate which extends across the end of the bar, triangular

side portions which extend from said end plate along the outer sides of the flanges of the bar, each of said triangular side portions having one edge thereof parallel and coincident with the adjacent edge of the flange of the bar, and having a securing flap which extends from said side portion throughout the length of said edge of said

side portion around the edge of the flange of the bar along the inner side thereof, 10
Witness my hand this 26 day of December, 1916.

MARTIN J. WUJEK.

M. SCHLECHT.

Certificate of Correction.

It is hereby certified that in Letters Patent No. 1,420,602, granted June 20, 1922, upon the application of Martin J. Wujek, of Buffalo, New York, for an improvement in "Shoes for the Legs of Metal Cots and Other Articles," errors appear requiring correction as follows: Page 1, strike out lines 95 to 107, comprising present claim 1, and line 108, strike out the numeral "2.;" and that the said Letters Patent should be read with these corrections therein that the same may conform to the record of the case in the Patent Office.

Signed and sealed this 5th day of February, A. D., 1924.
